(57) **CLAIM**

I claim the ornamental design for a rug cutting device, as shown and described.

DESCRIPTION

FIG. 1 is a left side elevational view of the design;

FIG. 2 is a right side elevational view thereof;

FIG. 3 is a front elevational view thereof;

FIG. 4 is a rear elevational view thereof;

FIG. 5 is a plan view thereof;

FIG. 6 is a bottom view thereof; and,

FIG. 7 is a perspective view thereof.

The broken line in FIG. 1 depicting a cutting blade is for illustrative purposes only and forms no part of the claimed design.
